UNITED STATES PATENT OFFICE.

THADDEUS C. JOY, OF TITUSVILLE, PENNSYLVANIA.

GRATE.

SPECIFICATION forming part of Letters Patent No. 279,250, dated June 12, 1883.

Application filed August 14, 1882. (No model.)

To all whom it may concern:

Be it known that I, THADDEUS C. JOY, a citizen of the United States, residing at Titusville, in the county of Crawford and State of Pennsylvania, have invented a new and Improved Grate, of which the following is a specification.

This invention relates to that class of shaking-grates in which the bars are provided with projecting teeth or short cross-bars and arranged to rock on bearings. Its objects are, first, to provide a grate of this class in which the bars may be worked smoothly and easily through a given range of motion for shaking out ashes and clinkers and loosening up the fuel, and may be turned farther to separate the short cross-bars by a sufficient distance to permit the contents of the grate to be dumped; second, to so construct and arrange the oscillating cross-bars of the grate that large lumps of coal cannot escape between the bars while they are being worked, and that clinkers and slate will be crushed between the ends of opposite rows of the cross-bars; third, to provide an independent end or side dump for the grate, in addition to the provision for dumping by turning the bars; fourth, to secure the bars against accidental displacement from their bearings, and to provide for the ready replacement of a broken or burned-out bar by a new one; and, fifth, to provide the grate with outside operating means which may be detached to permit the grate to be inclosed and readily connected for operating the grate when desired.

With these objects in view, my invention consists in certain novel constructions and combinations of devices, which will be hereinafter fully described, and pointed out in the appended claims.

In the drawings, Figure 1 is a perspective view of a grate constructed according to my invention. Fig. 2 is a section on the line $x-x$ in Fig. 1. Fig. 3 is a similar section, showing the cross-bars of the gate tilted, as in the act of shaking the grate. Fig. 4 is a perspective view, showing the grate dumped at the end or side, and having a portion of the base-plate broken away to expose to view the supports and operating-connections of the bars. Fig. 5 is a section through the bed-plate and one of the grate-bars and its supports on the line $y-y$

of Fig. 1. Fig. 6 is a similar section, showing the bar dumped at the end. Fig. 7 is a diagram, partly in section, illustrating the construction and operation of the stops which limit and adjust the extent of rocking motion of the grate bars or sections. Fig. 8 is a diagram taken at right angles to Fig. 7; and Fig. 9 is a similar diagram to Fig. 8, but illustrating the manner of dumping the grate by turning the bars with their bearing at one end and lowering the bars at their other end.

The letter A designates the bed-plate, having the edge surrounding the grate-opening notched, as shown at a , to permit the passage of ashes between the plate and the cross-bars of the grate.

B indicates the grate-bars, each of which consists of a supporting-shaft, b' , provided with transverse short bars b , the main portions of which project above the supporting-shaft, and are preferably straight or flat on their upper edges. These cross-bars are secured at the proper distance apart on the shaft by any ordinary or suitable means, and each cross-bar has its ends which stand adjacent to other bars notched or cut away on their lower edges to form stop-shoulder portions $c-c'$, the purpose of which will be presently explained. Those cross-bars which are upon the outer shafts have only their inwardly-projecting ends notched or toothed and their other ends are cut off to conform to the shape of the opening in the bed-plate. The opening may, however, be rectangular, in which case the cross-bars would not need to be cut off. The shafts b' of the grate-bars have their bearings at one end upon a bearing-bar, d , the ends of which are pivoted in lugs d' , which depend from the under surface of the bed-plate A, and each bar-shaft is provided with lugs or collars e , which project alongside the bearing-bar and prevent the shaft from moving endwise, and also prevent the bearing-bar from turning on its pivots when not required to do so. The opposite ends of the bar-shafts b' are supported on a crank-bar, f , the journals of which have their bearings in lugs f' , projecting from the under surface of the bed-plate. One of the ends of the crank-bar projects outwardly beyond its bearing, and is provided with an operating-handle, f'' . When the crank-bar is turned up

the tops of the grate-bars are supported on a level with and close the opening in the bed-plate, as shown in Fig. 1; but when the crank-bar is turned down the grate-bars are inclined 5 downwardly from their opposite bearings, as shown in Fig. 4, and permit the charge to be readily dumped at one side of the grate. From the under side of the bed-plate projects a rib, *g*, which prevents the bar-shafts *b'* from rising 10 from their bearings on the bearing-bar *d* when the grate is raised; but when it is lowered, as in Fig. 4, and as illustrated also in Fig. 6, the shafts are at such a distance from the rib *g* that they may be readily raised to clear the collar 15 or lugs *e* from the bearing-bar *d*, to permit the bars to be removed longitudinally. The ends of the shafts *b'* are preferably beveled on their upper surfaces to give room for raising them. Each of the grate-bar shafts *b'* has a down- 20 wardly-projecting arm, *h*, having at its lower end an outwardly-projecting pivot-pin, *h'*, and these pivot-pins enter bearings formed for them in an operating-bar, *i*, which is supported by the pivots. One end of this operating-bar is 25 extended beyond the bed-plate, as shown at *i'*, and has an upwardly-projecting pin, *i'*, with which is loosely engaged one end of a link, *k*, the opposite end of which is pivoted to the lower end of an operating-lever, *L*, which is 30 fulcrumed at the end of an arm, *l*, projecting from the bed-plate.

It is obvious that when the lever *L* is vibrated a rocking motion will be communicated to the grate-bar shafts *b'* through the intermediate connections which have just been described; and this rocking motion of the shafts will cause the cross-bars to oscillate, assuming inclined positions alternately in opposite directions, and thus shaking up the charge upon 35 the grate, and separating the ashes, clinkers, and slate from the live fire and fuel. In simply shaking the grate to clear it of ashes, slate, and clinkers, and to loosen up the fuel, the cross-bars should have a limited oscillation, 40 which will not permit them to so nearly approach a vertical position as to leave space enough between the grate-bars for the fuel to fall through, and in order to limit the rocking motion of the bar-shafts *b'*, and at the same 45 time provide for turning them sufficiently to dump the contents of the grate between the bars, when required, I provide adjustable stops *m m'*, which project from the under surface of the bed-plate and stand in the path of the 50 adjacent arms *h* of the shafts *b'*. These stops are simply metal blocks with projecting lugs *m'*, against which the arms *h* strike at the end of their movement. The blocks are secured to the bed-plate by slot-and-bolt connection, as 55 shown at *n*, so that they may be adjusted to permit the necessary limited rocking of the bars for shaking the grate, or may be set farther back to permit the grate-bars to be turned through nearly a quarter-revolution, and thus 60 bring the cross-bars to so nearly a vertical position that the fuel will all be dumped between 65

the grate-bars. The ends of the lugs *m'* are of such width that when the grate-bars are lowered at their dumping ends, the arms *h* will be carried so that they will not strike the stops, 70 and the bars may be therefore turned freely to assist the dumping. The lugs *m'* may be formed on slide-bars, which are held in place in any well-known manner, and thus the bolts and nuts be dispensed with. 75

The stop-shoulder portions *c c'* at the ends of the cross-bars *b* are an important feature of my invention.

It will be observed, referring to Fig. 3, that when the ends of one row of cross-bars are lowered the ends of the next are raised, and clinkers and pieces of slate will slide down the surfaces of one set of cross-bars and strike against the shoulders *c* and come under the overhanging portions *c* of the next row, so that 80 when the position of the bars is reversed the said slate and clinkers will be crushed, and thus prevented from clogging up the grate. Large pieces of coal cannot pass under the overhanging shoulder portions *c*, and so, in 85 case they strike the ends of the portions *c*, they will be shaken up into the fire, instead of escaping. 90

The link *k*, at the lower end of the operating lever *L*, it will be observed, is pivoted to swing vertically, and may be readily detached from the pin *i'* and allowed to hang freely downward. The object of this is to permit the space under the grate to be inclosed by a wall and access permitted to the operating-bar through 95 a small door, which may be closed ordinarily, or when the grate is not required to be shaken, and opened to permit the link *k* to be engaged with the pin *i'*. 100

What I claim as my invention, and desire to 105 secure by Letters Patent, is—

1. A rocking grate-bar comprising a long rocking shaft and a series of short cross-bars which are formed, respectively, with the notched portion *c c'*, which forms a stop-shoulder, and a bearing and breaking surface, substantially as and for the purpose described. 110

2. The combination of a plurality of rocking grate-bars, which respectively comprise a long rocking shaft and a series of short cross-bars, which are formed, respectively, with the notched end portion, *c c'*, which forms a stop-shoulder, and a bearing and breaking surface, substantially as and for the purpose described. 115

3. The combination, with the rocking grate-bar shafts *b'*, provided with the collars or lugs *e* at one end, of the bearing-bar *d*, entering between said collars, substantially as described. 120

4. The combination, with the grate-bar shafts *b'* and the bearing-bar *d*, of the collars or lugs *e*, projecting from the shafts on opposite sides of the bearing-bar, and the rib *g*, projecting downward from the bed-plate, and adapted to prevent the shafts from rising from their bearings, substantially as described. 125

5. The combination, with the rocking grate-bar shafts *b'*, having downward-projecting arms 130

h, of stops *m*, arranged to limit the rocking movement of said grate, substantially as described.

6. The combination, with the operating-bar *i*, connected with the grate-bars, of the operating-lever *L*, and the link *k*, adapted to be connected to or disconnected from the said operating-bar at will, substantially as described.

7. The grate having shafts *b'*, with arms *h*,

and adjustable stops *m*, arranged to permit said shafts to be rocked for shaking the grate or turned for dumping it, as required, substantially as described.
